UNITED STATES PATENT OFFICE.

PAUL BERGEN, OF RICHWOOD, WISCONSIN.

NON-REFILLABLE CONTAINER.

1,300,917.

Specification of Letters Patent. Patented Apr. 15, 1919.

Application filed May 20, 1918. Serial No. 235,679.

To all whom it may concern:

Be it known that I, PAUL BERGEN, a citizen of the United States, and a resident of Richwood, in the county of Dodge and State 5 of Wisconsin, have invented a new and Improved Non-Refillable Container, of which the following is a description.

My invention relates to what is generally termed a non-refillable bottle although 10 capable of use in being embodied in other containers having a neck. The invention particularly relates to a glass container, a portion of the neck of which is adapted to be broken off for gaining access to the container, means being provided to prevent the 15 refilling of the container otherwise than by breaking the neck.

The prime object of my invention is to improve the bottle sealing means, whereby 20 various advantages and numerous results are obtained, among which are the following: The fracture of the bottle neck will be required to follow predetermined lines, whereby the permanent neck portion will 25 not present a jagged form; the base portion or permanent part of the neck will have the strength to withstand the forcing of a cork therein after the upper portion of the neck has been broken off; the locking fingers for 30 locking the cap in place are given firm engagement within the bottle neck through the medium of a metallic bushing provided for the purpose as distinguished from engagement with shoulders or the like formed integrally on the inner wall of the neck; the 35 form and arrangement of the parts are such to promote simplicity and cheapness of manufacture, as well as convenience in producing the final assemblage.

Reference is to be had to the accompanying drawings forming a part of this specification, it being understood that the drawings are merely illustrative of one example of the invention.

Figure 1 is a central vertical section of a bottle neck having my invention applied thereto, parts being shown in positions forming a closure of the neck;

Fig. 2 is an inverted sectional plan view 50 taken in a plane corresponding with the line 2-2, Fig. 1;

Fig. 3 is a perspective view of the lock- 55 ing device;

Fig. 4 is a view similar to Fig. 1 but illustrating a slight modification of the inner 55 sleeve or inner bushing provided in the neck.

In carrying out my invention, a glass container 10 is provided with a neck 11 of suitable size. In order to weaken the neck in 60 a manner to determine the line of fracture, I give a novel form to the exterior of the neck a short distance from the base thereof. Weakened lines divide the neck into a larger upper section and a smaller lower section. 65 For the indicated purpose the neck is provided with a series of recesses 12 between which the neck presents vertical ribs or beads 13. In the beads 13 horizontal notches 14 are produced following the general 70 rounded lines of the neck, the notches thus serving to weaken the neck at the beads transversely of said beads. Also, to further determine the line of fracture, I produce shallow horizontal notches 15 in the material of the body of the neck 11 at the recesses 12 and in line with the notches 14. Thus, the notches 14, 15 make up an annular 75 series, the respective notches alternating and the whole producing a weakened annular 80 line broken in its continuity only at the sides of each bead 13.

A sealing cap 16 of generally inverted cup-shape is provided to cover the top of the neck and extend downward at the outside thereof. The said cap 16 carries locking fingers 17 which depend from the inner side of the top of the cap, four of such fingers being employed in the illustrated form and disposed 90° apart. The fingers 17 are 85 of spring metal and the lower ends 18 thereof are bent outwardly to produce hooks. In order to give a firm engagement to the hooked ends of the fingers, I provide the bottle neck with a bushing 19, the lower 90 edge of which is adapted to be engaged by said hooks. The bushing 19 may be secured in any suitable manner; in the form shown in Fig. 1 the bushing is formed with a top flange 20 to rest on the bottle neck and below said neck exterior threads are formed on the bushing to engage internal threads 100 on the bottle neck as indicated at 21. In the form shown in Fig. 4 the parts are the same except that an external depending annular flange 21a is formed on the outer edge 105

of the top flange 20^a and has internal threads to engage external threads on the bottle neck as indicated at 21^b.

In the illustrated construction, the fingers 17 are permanently secured to the cap 16 as follows: Said fingers are formed integral with a disk-like head 22, the planes of which fingers are bent downward, and said head is placed against the under side of the top 10 of the cap. An outer ring 23 extends about the head 22 between the same and the depending flange or skirt of the cap 16 and a second ring 24 is placed against the under side of the head 22 within the fingers 17. 15 The cap 16 has a central depending head 25, the base of which is contracted to form a neck 25^a. With the parts assembled in the cap 16, it being understood that the latter is inverted, molten metal 26 is poured into 20 the cap so that the elements 22, 23, 24, 25^a will be cast in said molten metal and held firmly in rigid relation to each other and rigid with the cap 16. The inner edge of the ring 24 is beveled as clearly shown in 25 Figs. 1 and 4 to allow a substantial amount of the molten metal 26 to extend about the contracted neck 25^a. The knob 25 is accommodated in a central opening 22^a in the head or disk 22. The ribs 13 give the otherwise 30 weakened neck the strength to withstand end pressure, and those portions of said ribs below the notches 14 serve, when the upper section of the neck is broken off, to strengthen the remaining portion against 35 the strain of forcing a cork therein.

I would state in conclusion that while the illustrated example constitutes a practical embodiment of my invention, I do not limit myself strictly to the mechanical details 40 herein illustrated, since manifestly the same

can be considerably varied without departure from the spirit of the invention as defined in the appended claims.

Having thus described my invention, I claim as new, and desire to secure by Letters Patent:

1. Closure means for the neck of a container, said means including a bushing adapted to fit in the interior of the said neck, a cap for the neck, and spring fingers 50 secured to the cap at the interior and depending from the top thereof, said spring fingers having a length to extend through the bushing and having hooked ends adapted to engage the lower edge of said bushing. 55

2. Closure means for the neck of a container, including a cap for the neck, spring fingers at the interior of the cap adapted to extend downward in the neck, rings inside and outside the fingers at the inner side of 60 the top, and metal cast in the interior of the cap and extending about the upper ends of the fingers and about the said inner and outer rings.

3. Closure means for the neck of a container, including a cap for the neck, spring fingers at the interior of the cap adapted to extend downward in the neck, rings inside and outside the fingers at the inner side of the top, and metal cast in the interior 70 of the cap and extending about the upper ends of the fingers and about the said inner and outer rings; together with a depending knob on the interior of the cap at the center, said knob having a contracted 75 base forming a neck uniting the knob with the cap, the said metal extending close about the neck of the knob, and means engageable by said fingers.

PAUL BERGEN.
